UNITED STATES PATENT OFFICE.

JAMES H. SHEAHAN, OF FREEPORT, ILLINOIS.

ROLLER-SKATE.

1,016,447.

Specification of Letters Patent.

Patented Feb. 6, 1912.

Application filed April 28, 1910. Serial No. 558,135.

To all whom it may concern:

Be it known that I, JAMES H. SHEAHAN, a citizen of the United States, residing at Freeport, in the county of Stephenson and State of Illinois, have invented a certain new and useful Improvement in Roller-Skates, of which the following is a specification.

This invention relates to roller skates, and 10 has for its object to provide a new and improved device of this description.

This invention is illustrated in the accompanying drawings, wherein—

Figure 1 is a side view showing a skate 15 embodying the invention; Fig. 2 is a front view of the skate shown in Fig. 1, with parts omitted; Fig. 3 is a view showing a modified construction.

Like numerals refer to like parts through- 20 out the several figures.

This invention has among other objects to provide a roller skate which can be used with greater safety than the ordinary roller skate, and which will prevent the skater 25 from falling backward when skating or when attempting to stop.

Referring now to the drawings, I have shown a skate having a frame 1, provided with front wheels 2 connected with the 30 frame by the support 3, and rear wheels 4 connected with the frame by the support 5. At the rear of the skate I provide a safety device 6 arranged so as to engage the surface over which the skater is traveling when the 35 skate tips backward, so as to prevent the skater from falling backward. This safety device may also act as a brake and is preferably adjustable. As shown in Fig. 1 it consists of a loop, one end of which is connected 40 with the rear portion 7 of the skate, the connection being preferably adjustable. As shown this construction is provided with a set screw 8, by means of which it may be fastened at different points along the portion 7 so as to lift or lower the safety device to adjust it as desired. The other end of the safety device is connected to the support 5. The device may be made inoperative when desired, in any suitable manner, as by being 45 entirely removed. The safety device is preferably provided with a rubbing surface 9 adapted to engage the floor when the skate is tipped up so as to drag therealong and act as a brake. The front wheels of the skate 50 are provided with some means for preventing their backward movement, but permit-

ting them to move forward freely. As herein shown the front wheels are rotatably mounted upon an axle 10, and are provided with a pawl and ratchet arranged so that the 60 wheels can move forward freely, but are prevented from rotating backward. I prefer to place the ratchet 11 on the wheel and the pawl 12 on a stationary part and in a position so that it may be normally held in contact with the teeth of the ratchet by its own weight. Any other arrangement may, of course, be used. This device prevents the 65 skate moving backward from under the skater so as to reduce the liability of falling 70 forward, while the safety device at the rear of the skate lessens the liability of the skate to move forward from under the user. Danger from accident, therefore, is very greatly reduced. The safety devices at both front 75 and rear are preferably arranged so as to be removed or rendered inoperative when desired. The front safety device may be easily rendered inoperative by simply lifting the pawl out of engagement with the ratchet 80 and holding it out of engagement by means of a pin 13.

In Fig. 3 there is shown a modified construction, wherein the safety device consists of the supporting part 14 to which is adjustably connected an adjustable part 15 which 85 engages the rubbing surface 9. A lock nut 16 is arranged to hold the adjustable part 15 in any desired position.

I claim:

1. A roller skate comprising a frame, front and rear wheels connected therewith, a loop at the rear of the frame having its ends connected at two separate points, the middle portion of the loop adapted to engage the 95 surface upon which the skate is supported when the frame is tilted about the rear wheels.

2. A roller skate comprising a frame, front and rear wheels connected therewith, a loop at the rear of the frame having its ends connected at two separated points, the middle portion of the loop adapted to engage the surface upon which the skate is supported when the frame is tilted about the rear 100 wheels, said loop adjustably connected with the frame so that its position may be varied.

3. A roller skate comprising a frame, front and rear wheels associated therewith, a projecting part associated with the rear wheels and adapted to engage the surface upon 105 which the wheels are supported when the

frame is tilted about the rear wheels and means associated with the front wheels for preventing backward rotation thereof.

4. A roller skate comprising a frame, front and rear wheels connected therewith, safety devices associated with said front and rear wheels and adapted to reduce the liability of the skate to move forward or backward

from under the user, and means for rendering said safety devices inoperative when desired. 10

JAMES H. SHEAHAN.
